CLAIM

The ornamental design for a collapsed cooler, as shown and described.

DESCRIPTION

FIG. 1 is a front elevation view of a collapsed cooler showing my new design;

FIG. 2 is a rear elevation view thereof;

FIG. 3 is a top plan view thereof;

FIG. 4 is a right side elevation view thereof, the opposite side being a mirror image;

FIG. 5 is a bottom plan view thereof;

FIG. 6 is a front elevation view of an alternate embodiment of FIG. 1;

FIG. 7 is a rear elevation view of FIG. 6;

FIG. 8 is a top plan view of FIG. 6;

FIG. 9 is a right side elevation view of FIG. 6, the opposite side being a mirror image;

FIG. 10 is a bottom plan view of FIG. 6;

FIG. 11 is a front elevation view of an alternate embodiment of FIG. 1;

FIG. 12 is a rear elevation view of FIG. 11;

FIG. 13 is a top plan view of FIG. 11;

FIG. 14 is a right side elevation view of FIG. 11, the opposite side being a mirror image;

FIG. 15 is a bottom plan view of FIG. 11;

FIG. 16 is a front elevation view of an alternate embodiment of FIG. 1;

FIG. 17 is a rear elevation view of FIG. 16;

FIG. 18 is a top plan view of FIG. 16;

FIG. 19 is a right side elevation view of FIG. 16;

FIG. 20 is a bottom plan view of FIG. 16;

FIG. 21 is a front elevation view of an alternate embodiment of FIG. 1;

FIG. 22 is a rear elevation view of FIG. 21;

FIG. 23 is a top plan view of FIG. 21;

FIG. 24 is a right side elevation view of FIG. 21, the opposite side being a mirror image; and,

FIG. 25 is a bottom plan view of FIG. 21.
